UNITED STATES PATENT OFFICE.

JOHN P. REILY, OF ST. LOUIS, MISSOURI.

BOOT OR SHOE HEEL.

1,272,098.

Specification of Letters Patent.

Patented July 9, 1918.

Application filed August 27, 1917. Serial No. 188,332.

To all whom it may concern:

Be it known that I, JOHN P. REILY, a citizen of the United States, residing at the city of St. Louis, State of Missouri, have invented a certain new and useful Improvement in Boot or Shoe Heels, of which the following is a full, clear, and exact description, such as will enable others skilled in the art to which it appertains to make and use the same, reference being had to the accompanying drawings, forming part of this specification.

My invention relates generally to foot-wear, and more particularly to a heel for boots, shoes and the like, the principal object of my invention being to wholly eliminate the leather now generally used in the manufacture of heels and to construct a comparatively simple and inexpensive heel from metal, rubber, wood, or the like, these elements being assembled so as to provide a very strong and substantial heel, the same being resilient or yielding to a certain degree, a portion of the heel capable of being easily and quickly removed in order to renew parts which have become worn or unfit for service.

A further object of my invention is to provide a heel having a plurality of readily insertible plugs, portions of which project from the underside of the heel to provide ground-gripping or engaging members, said plugs being preferably constructed of hardened metal in order to resist wear, and thereby materially strengthen the life or term of service of the heel.

With the foregoing and other objects in view, my invention consists in certain novel features of construction and arrangement of parts hereinafter more fully described and claimed and illustrated in the accompanying drawing, in which—

Figure 1 is a vertical section taken centrally through the rear portion of a boot or shoe and showing a heel of my improved construction applied thereto;

Fig. 2 is a perspective view of the upper member of the housing which forms the body of my improved heel;

Fig. 3 is a perspective view of the lower member of the housing;

Fig. 4 is a perspective view of a filler

block which is positioned in the upper portion of the upper member of the housing;

Fig. 5 is a perspective view of an elastic or yielding filler member which is positioned in the central portion of the housing forming the body of the heel;

Fig. 6 is a perspective view of one of the insertible plugs forming a part of my improved heel;

Fig. 7 is a detail section taken approximately on the line 7—7 of Fig. 1;

Fig. 8 is a detail section illustrating a modified form of the insertible plug utilized in my improved heel.

Referring by numerals to the accompanying drawing, 10 designates the vamp of a boot or shoe, 11 the outer sole, 12 the insole, and 13 the heel seat. The heel contemplated by my invention includes a housing, the same being formed in two parts and shaped similar to the ordinary leather heels now in general use. The upper part of the housing comprises a plate 14 which is slightly concave so as to fit snugly against the heel seat 13, said plate being provided with suitably located apertures 15 which receive tacks, screws, or like fastening devices which serve to firmly secure the upper part of the housing to the rear portion of the sole of the boot or shoe.

Formed integral with the edge of plate 14 is a depending wall 16, and formed integral with the lower edge of said wall is a depending flange 17, the same being approximately half the width of the wall 16. The lower part of the housing comprises a plate 18 in which is formed a series of openings 19 adapted to receive the insertible plugs hereinafter more fully described; and formed integral with the edge of this plate 18 is an upwardly projecting wall 20. Formed integral with this wall and projecting upwardly therefrom is a flange 21, the same being approximately half the thickness of the wall 20. Flange 17 depends from the inner portion of wall 16, and flange 21 projects upwardly from the outer portion of wall 20 so that when the two parts of the housing are properly assembled, flange 21 overlies flange 17, as illustrated in Fig. 1. The means utilized for locking the lower or removable portion of the housing com

prises a flat spring 22 which is fixed to the inside of the front portion of flange 17, the free end of said spring being provided with a hook 23, which latter extends horizontally outward through an aperture 24 formed in the front portion of flange 17. Formed in the front portion of flange 21 is an aperture 25 which is adapted to receive the outer end of hook 23 when the two parts of the housing are properly assembled (see Figs. 1 and 7). The two parts of the housing are preferably constructed of metal, either cast, or of sheet metal pressed to proper shape.

Removably positioned within the upper portion of the upper member of the housing, and bearing directly against the underside of plate 14, is a block or plate 26 of wood or analogous material. Positioned beneath said block or plate is a section 27 of rubber or analogous resilient material, the same being provided with an upwardly projecting marginal rib 28 which bears directly against the underside of the block or plate 26.

The insertible plugs forming a part of my improved heel, are preferably constructed of hardened metal blocks 29 of such size and shape as to be readily fitted through the openings 19 in plate 18 the tops of said plugs being provided with outwardly projecting flanges 30 which bear directly on top of the plate 18 around the edges of the openings 19 therein, and said flanges bearing directly against the underside of the rubber section 27. The tops of these plugs are preferably recessed, as designated by 31, in order to form pockets from which the greater portion of the air is exhausted when the blocks are pressed upwardly against the rubber section 27, such action creating suction to cause the plugs to adhere to the underside of said rubber section. The undersides of the plugs 29 are preferably milled or corrugated, as designated by 32, such construction enabling the plugs to firmly grip the ground or surface with which they are in contact and eliminating any tendency to slip on smooth or wet surfaces. While I prefer to form these plugs or studs of hardened metal, it will be understood that in some instances it may be found desirable to form them of rubber or a suitable composition.

In the modified construction illustrated in Fig. 8, the insertible plugs are shown in the form of spherical bodies, the same being preferably formed of hardened metal and projecting through suitably formed openings in the bottom of the housing.

A heel of my improved construction is comparatively simple, can be easily and cheaply manufactured, and is provided with a series of hardened metal plugs or ground engaging studs which normally bear against an elastic or yielding member, and said

plugs or studs being readily removable to permit of their being taken out and replaced when they become worn to such a degree as to be unfit for service. The housing or body of the heel may be made of comparatively heavy material with the result that a very strong and durable structure is produced, the same being particularly applicable for use on the footwear of persons whose duties involve a considerable amount of walking, and likewise for persons engaged in farm-work, mining, and the like.

It will be readily understood that minor changes in the size, form and construction of the various parts of my improved heel may be made and substituted for those herein shown and described, without departing from the spirit of my invention, the scope of which is set forth in the appended claims.

I claim:

1. A shoe heel comprising a housing, the lower portion of which is removable, a filler block in the upper portion of said housing, an elastic body within the housing below said filler block, and a plurality of independently movable studs positioned within the housing beneath the elastic member, portions of which studs project through the bottom of the housing.

2. A shoe heel comprising a housing formed in two parts one of which is removably positioned upon the other, an elastic body within said housing, and a plurality of independently movable hardened metal studs removably positioned in the housing and bearing against said elastic body.

3. The herein described heel comprising a housing the bottom of which is provided with a series of openings, an elastic body within said housing, and a series of independently movable metal studs bearing against said elastic body and projecting through the openings in the bottom of said housing.

4. The herein described heel comprising a housing, a filler block positioned therein, an elastic member within said housing beneath the filler block, and a series of metal studs removably positioned in the bottom of the housing and bearing against said elastic member.

5. The herein described heel comprising a housing having a detachable portion, hardened metal studs removably positioned in the removable part of the housing, and a yielding member within said housing against which said studs normally engage.

6. The herein described heel comprising a housing having a removable part, means for locking the removable part of the housing to the other part, an elastic member within the housing, and a series of metal studs bearing against said elastic member and projecting through the bottom of the housing.

7. A shoe heel comprising a housing having a removable part, means for locking said removable part of the housing to the other part, a filler block located in the upper 5 part of the housing, an elastic member located below the filler block, and a series of independently movable studs bearing against

the underside of the elastic member and projecting through the bottom of the removable portion of the housing. 10

In testimony whereof I hereunto affix my signature this 24th day of August, 1917.

JOHN P. REILY.
